DEFIBERIZING DEVICE

Neil C. Ward, Chicago, Ill., assignor to Anderson-Tully Company, Memphis, Tenn., a corporation of Tennessee

Application July 9, 1932, Serial No. 621,561

4 Claims. (Cl. 83—75)

The present invention relates to defiberizing wood and other material. It has to do particularly with such material when it has been softened by water treatment or is green.

Many uses have been found for the fibers of wood. This is particularly true when the fibers have been obtained in an undamaged condition and in their natural lengths. The present invention brings forth fibers in a softer and more usable condition than has ever heretofore been possible.

To obtain the best results, it has been found desirable to reduce bundles of fibers to single fibers whenever such has been possible. Groups of a few fibers are highly useful. The present invention is effective for providing single separate fibers and bundles of a few fibers all of their natural length.

Among the objects of the invention are the following:

20 A new and highly efficient machine for the reduction of wood and the like to its fibrous constituents.

A novel device for producing full length individual fibers or bundles of fibers of a relatively small number of individual fibers.

Better means for the disintegration of wood and the like into its fibrous units.

A novel means and process for tearing wood into its individual fibers or bundles of a few fibers each without destroying the fibers themselves.

30 A new and novel means for applying a disintegrating force to wood or the like whereby the fibers of the material are separated into individual fibers or into bundles of a few fibers each.

A machine of rigid disintegrating members capable of maintaining their rigidity while contacting the material which is being disintegrated.

40 These objects, and such other objects as may hereinafter appear, are obtained by the novel construction, unique arrangement and improved combination of the several elements which constitute the forms of the invention illustrated herein, such forms being but a few of a number of forms which the invention may take.

In the drawing which is employed to illustrate such forms of the invention herein described:—

Figure 1 is a vertical section through an assembly of parts used for the defiberizing operation herein described, such parts embodying means for practicing the invention;

Figure 2 is a plan view of said form of the invention;

55 Figures 3, 4 and 5 are sectional views of forms

which the defiberizing belt may take; and

Figures 6 and 7 are plan views of the belts shown in the preceding figures.

Like reference characters are used to designate similar parts in the drawing and in the description of the invention which follows.

The defiberizing device herein described is mounted upon a base 10. Said base may comprise any suitable uprights and horizontal members with brace members as required. Upon base 10 are standards or brackets 11 of suitable number, between the end two of which a belt 17 is made to operate.

For handling belt 17, there are a suitable number of pulleys. A driving pulley 12, driven pulley 13, and an idler 14, are shown. Each of the said pulleys is journaled in a pair of said brackets. Pulley 12 is driven by a belt 15 which travels about a pulley 16 keyed to or otherwise attached to pulley 12. Other driving means may be substituted for belt 15.

The position of pulleys 12, 13 and 14 is such that the belt 17 which extends thereabout is held in a substantially horizontal plane in respect to its top flight, the tension upon the belt 17 being such that no sag or very slight sag occurs therein at any point. Idler 14 is to aid the prevention of sag. The belt 17 preferably is driven at high speed.

Over the belt 17 is a hopper 20. The walls of said hopper may be straight as is shown in the drawing, Figure 1. Its lower edges at its ends are in close proximity to the tips or points or prongs or teeth on the belt whereby to prevent material escaping between the hopper and the belt.

At one end of the device, there may be a discharge chute or hopper 23, as shown. The discharge hopper 23 encloses an area extending over pulley 12. In the hopper is a blower 18, by which material is forced therewith and out of discharge spout 19.

The belt 17 may comprise a flexible member 24. Suitably secured therein and preferably extending wholly therethrough are prongs or teeth 25. (Figure 3.) Said prongs or teeth may have heads 26 the under side of which rest against the inner side of the belt. Such heads furnish means for securing the prongs in position in the texture of the belt in addition to the frictional engagement of the shank of the teeth with the material of the belt.

Each of the prongs has a sharply pointed section 26 which comes into contact with the wood or other material to be disintegrated. The ar-

arrangement of the teeth is staggered. The projection of the prong 25 above the body of the belt is relatively slight but enough to insure the engagement of the end of the prong with wood in a plane measurably above the plane of travel of the top flight of the belt. The shape of the prong should admit of its ready discharge of fibrous material which collects therein. Each prong is of a material and has body sufficient to prevent it from bending upon contacting wood or other material. Such prong or tooth may be described as rigid pointed members.

The described flexible belt may be of leather or of other suitable belt material which has thickness sufficient for holding the prongs 25 against displacement from the material of the belt.

A metal device may be substituted for the leather belt. The metal belt or chain 30 should be flexible. It may be of coupled links. Whatever form the belt takes, it should have pointed teeth 31 and the teeth should be in staggered arrangement. If staggering is impracticable, then oscillatory means may be supplied to cause lateral displacement of the aligned teeth during the travel of the teeth from one end of the top flight of the belt to the opposite end. The teeth may be like those employed for a rotary saw or the like or the teeth may resemble in contour the teeth of a link saw. By forming the metal belt 30 in sections 32, each of which is relatively narrow, and in which the teeth 31 of each adjacent section are in staggered arrangement, as is shown in Figure 7, a highly efficient disintegrator is had. In Figures 4 and 5, teeth attached to belts of metal are shown. In the former, the teeth extend through the belt, while in Figure 5, the prongs are welded into position in the top surface of the belt.

The belt normally should travel about six thousand feet a minute. It may be made to travel faster. Wood blocks or other materials which are fed into the hopper rest upon the prongs when such materials attain the bottom of the hopper. Such blocks generally are not placed in the hopper until the belt has been put in motion.

As the belt is travelling at high speed, there is no opportunity for the prongs 25 or teeth 31 to bite deeply into the wood or other material which rests on the belt, but on the contrary, the prongs rasp or scrape the outer surface of the wood, pulling therefrom the individual fibers, or where it does not disintegrate the fibers into single units, the teeth or prongs tear from the wood block or other material bundles formed of a small number of fibers. Rigidity of the teeth maintains the point contact of the teeth and prevents the teeth bending to present a portion of the body instead of the points.

Wood before being put in the device should be thoroughly soaked, if it has been previously dried. Green wood does not require moistening. The fibers then are readily torn from the body of the wood as individual fibers, each of which is adapted to remain in unitary condition as soon as dried following the disintegration of the wood or other material from which it is obtained.

As the fibers are pulled or drawn from the wood block, they are carried by the force of the belt to the end of the housing and are discharged by way of the chute provided therefor, the blower aiding in such discharge.

The pressure at which the wood is disinte-

grated is relatively slight for the surface area provided by the belt is quite large, thus distributing the weight of a block of wood or other material to reduce the pressure of the wood upon the belt when measured in terms of area.

Because the belt travels at high speed, and because the belt is maintained taut during the entire operation, and for the further reason that the teeth are rigid enough to prevent bending axially, the action of the belt, whether it be of the one style or of the other, is like that of a lightly applied rasp or file. While the action of the belt is constant, the force of the teeth is actually gradually applied with the result that the device produces fibers in their individual state or in bundles of a few fibers. It usually disintegrates the fibers in their full length and in a soft condition.

If desired, material may be fed into the hopper so that the fibers are removed longitudinally of the material or transversely as desired. Suitable guides may be affixed to the hopper to hold the material in a selected relationship to the belt, i. e., longitudinally or transversely thereof.

As shown in the drawing, the area of the surface of the tooth carrying member engaging a block of wood is greater than the area of the surface of any block of wood in contact with it. The teeth are arranged so that succeeding teeth are not moved in paths in pronounced linear alignment in the direction of a movement of the belt or other carrying member.

Instead, succeeding teeth are disposed, as is shown in Figure 6, to travel in different but adjacent linear paths, the paths generally being parallel and quite close together. In this manner, one entire surface of a block of wood or the like is at all times under treatment, and the teeth are engaged with the whole of the exposed surface of the block of wood and are not travelling in well defined, spaced apart paths producing grooves in the block of wood. On the contrary, the travel of the teeth is in promiscuous parallelism without possibility of "grooving" the contacted face of the block of wood.

What is claimed as new and is desired to be secured by Letters Patent of the United States is:

1. A means for disintegrating a block of wood or the like into fibers, and comprising a receptacle for holding in a selected angular position wood to be treated, a belt having separate teeth in staggered relationship for engaging material in said receptacle, the area of said belt having teeth in contact with such block of wood being greater than the area of the surface of the block of wood under treatment, means for moving said belt, roller means for guiding said belt across said receptacle with each tooth in a substantially straight linear path and with the exposed ends of said teeth operating substantially in a single plane while in engagement with material in said receptacle, rotary means for driving said belt at high speed, and suction means at the extreme of the movement of said belt in its path under said holding means for removing disintegrated wood.

2. A device for disintegrating fibrous material such as wood, comprising an endless belt, supporting means for said belt providing a substantially flat top flight therefor, means for driving said belt at high speed, rigid teeth in staggered relationship on said belt and having points projecting upwardly on the top flight thereof and moving with said belt with such points in contiguous or overlapping paths, a bottomless hopper

over the top flight of said belt and limited in horizontal extent to the area of said top flight, and pneumatic means for removing disintegrated material from said belt.

- 5 3. A device for disintegrating fibrous material such as wood, comprising an endless belt, rollers carrying said belt and providing a substantially flat top flight therefor, means for driving said belt in one direction, rigid teeth in staggered relation-
10 ship on said belt and having points projecting upwardly therefrom, a bottomless hopper over the top flight of said belt and limited in horizontal extent to the area of said top flight, a housing at the end of the top flight of said belt toward which
15 the top flight is driven and extending from said hopper to a position removed from said hopper

and said top flight but adjacent said belt, and suction means in connection with said housing and operable to remove disintegrated material from said belt.

4. A belt for use in defiberizing wood, comprising rigid teeth adapted to support the weight of wood to be defiberized, and an endless flexible tooth carrying member, said teeth consisting of pins set in said member in staggered positions longitudinally and transversely of said member, the latter including means for maintaining said teeth upright and in position while the teeth support the weight of the wood and remove fibers therefrom.
